CUTTER CHAIN

Francis E. Sullinger, Claremont, N. H., assignor to
Joy Manufacturing Company, a corporation of
Pennsylvania

Application July 10, 1944, Serial No. 544,208

4 Claims. (Cl. 262—33)

This invention relates to cutter chains and more particularly to an improved chain block and bit holder for a cutter chain especially designed for use in the cutting of coal or the like.

An object of the present invention is to provide an improved cutter chain. Another object is to provide an improved cutter chain having improved means for securing a cutter bit in cutting position on the chain block lug. A further object is to provide an improved chain block lug of a novel design. A still further object is to provide an improved bit holder for securing a cutter bit on the block. Still another object is to provide an improved bifurcated bit holder adapted to straddle the lug of a chain block. Yet another object is to provide an improved pivotal mounting for the holder on the chain block. Other objects and advantages of the invention will, however, hereinafter more fully appear.

In the accompanying drawing there is shown for purposes of illustration one form which the invention may assume in practice.

In this drawing:

Fig. 1 is a side elevational view of a cutter chain constructed in accordance with an illustrative form of the invention.

Fig. 2 is a cross sectional view taken substantially on line 2—2 of Fig. 1.

Fig. 3 is a view in central longitudinal vertical section taken substantially on line 3—3 of Fig. 2.

Fig. 4 is a fragmentary side elevational view of the bit, block and holder, illustrating the manner of removing the cutter bit from the block.

Fig. 5 is a sectional view taken substantially on lines 5—5 of Fig. 1.

Fig. 6 is a perspective view of the improved chain block.

Fig. 7 is a perspective view of the cutter bit.

Fig. 8 is a perspective view of the improved bit holder.

In the illustrative embodiment of the invention disclosed herein, there is shown a cutter chain comprising a chain block 1, strap links 2 and pivot pins 3 for pivotally connecting the block and links together.

The chain block has a lateral lug 4 provided with vertical grooves or recesses 5, 5 at its opposite sides, and a horizontal upper plane surface 6, disposed at right angles to the grooves and extending therebetween, provides a seat for the inner end of a cutter bit. Upstanding from the lug at the forward side of the grooves is an abutment 7 providing a rearwardly facing, forwardly and outwardly inclined surface 8. The block lug at the rear sides of the grooves 5 is trans-

versely arcuately slotted at 9, and the narrow central portion 10 of the lug between the grooves 5 has a transverse opening 11. Threaded within an inwardly and downwardly inclined opening 12 at the forward side of the lug is an adjustable element herein preferably a set screw 13. The opening 12 cuts through at 14 the sides of the narrow portion 10 of the lug at the bottoms of the vertical grooves 5 so that the inner end of the set screw projects into the grooves.

The improved bit holder is generally designated 15 and comprises an outer head 16 and an inner shank 17. The holder head is recessed or socketed at 18 for the reception of a cutter bit, and, as clearly shown in Fig. 8, the shank is bifurcated so that the holder straddles the block lug with spaced apart, parallel side portions 19, 19 of the shank received in the lug grooves 5. Thus the outer surfaces of the holder lie substantially within the lateral limits of the block. The side portions 19 of the holder shank have curved projections 20 at their rearward sides, and these projections are shaped to fit the transverse grooves 9 to provide a pivotal mounting for the holder. A transverse pin 21 is fitted in the opening 11 and projects within openings 22 in the side portions of the shank to secure the holder on its pivotal mounting. The shank portions 19 have inclined forwardly facing surfaces 23 with which the inner end of the set screw engages concurrently for swinging the holder on its pivotal mounting. The upper portions of the rear walls of the lug grooves are rearwardly inclined at 24 to permit free swinging of the holder on its pivotal mounting 9, 20.

The cutter bit is generally designated 25 and is of a conventional design provided with a pair of cutting points so that the bit may be reversed when one cutting point becomes dull. The bit body is generally of triangular shape in side elevation and has plane cutting faces 26, 26 lying in the sides of the triangle and terminating in cutting points 27 at the opposite extremities of the bit body. The body is generally diamond shape in cross section and the cutting faces are of elongated diamond shape in outline, as shown in Fig. 7.

When the cutter bit 25 is in cutting position on the chain block, its inner inactive cutting face rests on the upper plane surface 6 of the block lug, and the bit body is received in the recess 18 in the holder head, and the head-recess is V-shaped to conform to the upper portion of the bit, as shown in Fig. 2. The inner portion of the active cutting face of the cutter bit rests against

the inclined surface 8 on the front abutment 7. When the set screw 13 is adjusted inwardly in the opening 12, its inner end engages both of the side portions of the holder shank, and the holder is swung on its pivotal mounting to clamp firmly the cutting faces of the bit against the surfaces 6 and 8 on the block. When it is desired to release the cutter bit, the set screw may be loosened to permit swinging of the holder on its pivotal mounting into the position shown in Fig. 4 so that the bit may be removed forwardly from the holder recess over the top of the front lug 7.

As a result of this invention an improved cutter chain is provided wherein a cutter bit is held in cutting position on the chain block in an improved manner. By the provision of the grooved block lug and the bifurcated holder, an extremely rugged and simple construction is attained. By the improved pivotal mounting for the holder and the arrangement of the holder on the block lug, the cutter bit is firmly clamped in cutting position on the block, and the bit may be readily released when desired. Other uses and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a cutter chain, a chain block having a lateral lug provided with vertical grooves at its opposite sides, a bit holder having an outer head and an inner shank, said head being recessed for the reception of a cutter bit, and said shank having parallel side portions receivable in said grooves, a pivot connection between said shank and said block lug for permitting pivotal movement of said holder relative to said block, and means on said block for engaging the side portions of said holder shank for swinging said holder in said grooves into bit clamping position relative to said block.

2. A chain block having a lateral lug, said lug having vertical grooves at its opposite sides adapted to receive portions of a bit holder, and

said lug having a plane outer surface extending between said grooves and against which a cutter bit is adapted to seat, and said lug having at the rear sides of said grooves portions providing a pivotal mounting for a bit holder.

3. In a cutter chain, a chain block having a lateral lug provided with vertical grooves at the opposite sides, a bit holder having an outer head and an inner shank, said head recessed for the reception of a cutter bit and said shank having spaced parallel side portions receivable in said grooves, means at the rear sides of said holder and grooves providing a pivotal mounting for said holder, and a set screw at the front of said block engaging the side portions of said shank for swinging said holder on its pivotal mounting to effect clamping of the cutter bit in cutting position on the block lug.

4. In a cutter chain, a chain block having a lateral lug provided with recesses in its opposite sides, a swingable holder for securing a cutter bit in cutting position on said block comprising an outer head recessed to receive a cutter bit and a bifurcated inner shank, said holder straddling said block lug with the side portions of said shank received in said recesses, a pivotal mounting for said holder at the rear sides of said recesses, and means on said block for engaging said holder shank for swinging said holder on its pivotal mounting.

FRANCIS E. SULLINGER.
